Attorney

UNITED STATES PATENT OFFICE.

SAMUEL J. WILSON, OF ROBERTS, IDAHO, ASSIGNOR OF ONE-HALF TO PERRY BASINGER, OF CLYDE, IDAHO.

BEET-TOPPING APPARATUS.

1,393,871.

Specification of Letters Patent. Patented Oct. 18, 1921.

Original application filed January 11, 1919, Serial No. 270,691. Divided and this application filed March 10, 1920. Serial No. 364,801.

To all whom it may concern:

Be it known that I, SAMUEL J. WILSON, a citizen of the United States, residing at Roberts, in the county of Jefferson and 5 State of Idaho, have invented certain new and useful Improvements in Beet-Topping Apparatus, the same being a division of my co-pending application, Serial No. 270,691, of which the following is a specification, 10 reference being had to the accompanying drawings.

This invention relates to certain improvements in beet harvesters and has relation more particularly to a rotary lifting member, and it is an object of the invention to provide a lifting member with improved penetrating members coacting with the severed crowns of the beets to convey the same upwardly to a desired point of delivery. 15

20 The invention consists in the details of construction and in the combination and arrangement of the several parts of my improved harvester whereby certain important advantages are attained and the device rendered simpler, less expensive and otherwise more convenient and advantageous for use, as will be hereinafter more fully set forth.

25 The novel features of my invention will hereinafter be definitely claimed.

30 In order that my invention may be the better understood, I will now proceed to describe the same with reference to the accompanying drawings, wherein:

35 Figure 1 is a fragmentary view partly in side elevation and partly in section illustrating a rotary lifting member constructed in accordance with an embodiment of my invention;

40 Fig. 2 is a view in front elevation of one of the penetrating members carried by the rotary lifting member, said rotary lifting member being fragmentarily shown in section;

45 Fig. 3 is a view in side elevation of the penetrating member as disclosed in Fig. 2, the coacting portion of the rotary lifting member being also indicated in section; and

50 Fig. 4 is a fragmentary view illustrating in top plan the penetrating member as disclosed in Figs. 2 and 3.

As disclosed in the accompanying drawings, R denotes a rotary lifting member supported in a manner particularly described and illustrated in my co-pending applica-

tion, Serial No. 270,691, filed January 11, 55 1919, and of which the present application is a division. In practice, the member R is in close proximity to the digging element 32 in advance thereof and rearwardly of the cutting means 58 and also in close proximity to but free of contact with the ground level. The member R is cylindrical in form and includes an annular rim 11 of desired width and radiating from said arm 11 are the penetrating teeth M. 65

The teeth M comprise a plurality of series disposed transversely of the rim, said series of teeth being preferably equidistantly spaced with the teeth M of one series staggered with relation to the teeth of adjacent 70 series. As is illustrated in Figs. 2, 3 and 4, each of the teeth M comprises a blade 12 having its outer end portion 14 pointed and with its opposite faces convex so that the edges of the blade 12 are substantially sharp. 75 The inner or base portion of the blade 12, at substantially its center, is provided with a shank 15, preferably square in cross section, and which snugly fits within the correspondingly formed opening 16 produced 80 in the rim 11 of the member R. The outer portion 15' of the shank 15 is circular in cross section and has threaded thereon a clamping nut 17 which coacts with the inner or under face of the rim 11 to maintain 85 effectually the tooth M in applied position.

As is particularly illustrated in Figs. 2 and 3, the edges of the blade 12 are disposed in a direction substantially at right angles to the axis of the member R or more 90 particularly the shaft 10 upon which the same is mounted. The outer or pointed extremity 14 of the blade 12 is provided with the outwardly and oppositely directed ribs 18, each preferably substantially in the form 95 of an inverted triangle with the free edges thereof sharpened. The ribs 18 are also disposed in a direction longitudinally of the member R or in a direction transversely of the frame F. The member R is adapted to 100 be rotated in any desired manner but more particularly by the mechanism or means disclosed in my prior application hereinbefore referred to and of which the present application is a division. 105

In practice, as the machine proper advances, the means 58 cut into the crowns of the beets and about the time the crown is

completely severed, the same is penetrated by one or more teeth M of the member R at a point slightly in advance of the vertical center of the member. The severed crown is 5 carried upwardly by the member R to a suitable point of delivery as is particularly described and illustrated in my prior application hereinbefore referred to.

From the foregoing description, it is 10 thought to be obvious that a harvester constructed in accordance with my invention is particularly well adapted for use by reason of the convenience and facility with which it may be assembled and operated, and it will 15 also be obvious that my invention is susceptible of some change and modification without departing from the principles and spirit thereof, and for this reason I do not wish to be understood as limiting myself to 20 the precise arrangement and formation of the several parts herein shown in carrying out my invention in practice except as hereinafter claimed.

I claim:—

25 1. A machine of the character described including a movable member, spaced teeth

carried by said member, each tooth having convex sides merging with each other at their edges, ribs projecting from the intermediate portion of said sides longitudinally thereof, said ribs and convex sides tapering toward and merging at a point centrally of one end of the tooth, and opposed lips projecting from said tapered end in alignment with each other and in right angular relation to said convex sides. 30

2. A machine of the character described including a movable member, spaced teeth carried by said member, each tooth having convex sides merging with each other at their edges, ribs projecting from the intermediate portion of said sides longitudinally thereof, said ribs and convex sides tapering toward and merging at a point centrally of one end of the tooth, and opposed lips projecting from said tapered end of the tooth, 40 the ends of said lips terminating at said end of the tooth, the sides of said lips projecting beyond the longitudinal ribs of the tooth. 45

In testimony whereof I hereunto affix my signature.

SAMUEL J. WILSON.
